UNITED STATES PATENT OFFICE

168,613

FOOT SPRAYING DEVICE

Ivanhoe Peter Denyssen, Merion, Pa., assignor, by
mesne assignments, to Sani-Mist, Inc., Phila-
delphia, Pa., a corporation of Pennsylvania

Application January 2, 1951, Serial No. 13,651

Term of patent 14 years

(Cl. D83--1)

To all whom it may concern:

Be it known that I, Ivanhoe Peter Denyssen, a citizen of the United States, residing in Merion, county of Montgomery, Commonwealth of Pennsylvania, have invented a new, original, and ornamental Design for a Foot Spraying Device, of which the following is a specification, reference being had to the accompanying drawing, which forms a part thereof.

Figure 1 is a front perspective view of a foot spraying device showing my new design; and

Figure 2 is a rear perspective view thereof.

The dominant features of my design reside in the portions shown in full lines.

I claim:

The ornamental design for a foot spraying device, as shown and described.

IVANHOE PETER DENYSSEN.
